UNITED STATES PATENT OFFICE.

JOHN F. HUCKEL, OF KANSAS CITY, MISSOURI, ASSIGNOR TO FRED HARVEY, OF KANSAS CITY, MISSOURI.

DESIGN FOR A LUNCH-COUNTER STOOL.

Application filed September 13, 1926. Serial No. 19,044. Term of patent 14 years.

To all whom it may concern:

Be it known that I, JOHN F. HUCKEL, a citizen of the United States, residing at Kansas City, Jackson county, Missouri, have invented a new, original, and ornamental Design for Lunch-Counter Stool, of which the following is a specification, reference being had to the accompanying drawing, forming part thereof.

In the drawing:

Fig. 1 is a front, elevational view of the stool, showing my new design.

Fig. 2 is a side elevational view of the same.

Fig. 3 is a rear view of the same.

I claim:

The ornamental design for a lunch counter stool as shown.

JOHN F. HUCKEL.
